ALBERT HALLOWELL AND ABEL T. ATHERTON, OF LOWELL, MASSACHUSETTS.

Letters Patent No. 96,228, dated October 26, 1869.

GAS FLAT-IRON.

The Schedule referred to in these Letters Patent and making part of the same.

To all whom it may concern:

Be it known that we, ALBERT HALLOWELL and ABEL T. ATHERTON, both of Lowell, in the county of Middlesex, and State of Massachusetts, have invented certain new and useful Improvements in Gas Flat-Irons, of which the following is a full, clear, and exact description, reference being had to the accompanying drawings, making part of this specification, in which—

Figure 1 represents a plan of the interior, and a portion of the exterior, after the cover *k* has been removed.

Figure 2 is a longitudinal vertical section, and

Figure 3, a plan of the under side of the cover, with the reflecting or radiating-plate *f* arranged thereon.

Figure 4 is a modification of our invention.

This invention has for its object to heat the hollow flat-iron by the flame of burning gas, without creating smoke or offensive odor, by supplying the flame with oxygen, to support free combustion through the tubes of the burners.

This invention consists in the combination of two devices, both of which are patented, and one to each of the applicants—the first to ATHERTON, in 1866, August 7, and the second to HALLOWELL, in 1868, March 17; and this invention is intended as an improvement upon these two, by combining them, as shown in the drawings.

The construction of the hollow flat-iron or sad-iron, and the arrangement of the heat-conveying pillars *j* and the chimney *A*, the rear stand *B* and the handle *C*, may be about as shown in the drawings; and the mode or means of heating a hollow sad-iron, and which we have found best adapted for that purpose, consists of a series of about three of the peculiar gas-burners here shown, and these burners are connected, or formed on the side of a gas-receiver and distributor, *D*, which has a hub, *a*, rising from its top, to receive a supply-pipe, *E*, to the outer end of which we apply a flexible tube, *F*, as usual.

The receiver *D*, and about half the length of the burner-tubes, are wholly outside of the hollow sad-iron.

The tubes enter through the rear end *G*.

The centre tube *b* is shouldered against the outside of the end-piece, and a nut, *H*, screwed on to the tube inside of this end-piece, holds the burners and the gas-receiver and supply-pipe in position.

The gas passes from the distributor, through a very small orifice, *c*, to the much larger one, *g*, and out at the end *d* of each burner-tube.

Atmospheric air, to supply the flame, enters a side-orifice, *e*, passing through the centre *g* with the gas which, when burning, creates a strong draught through each burner-tube, acting like a blow-pipe, to intensify

the heat, and carry it forcibly to the forward extremity of the cavity within the iron, and to each pillar, as shown by arrows.

The pillars, being formed or cast with the bottom *h*, transmit the intensified heat readily and rapidly to the bottom and face of said iron, and keep it heated to the desired degree.

The pillars are not in solid connection with the top plate *f* or reflector, as in the former invention, but the plate merely rests on some of the pillars, and this retards the upward action of heat, and helps to keep it in the lower space; but there must be an outlet for the surplus heat, and for the atmospheric air consumed by the gas-flames.

For this purpose, we form an opening, *I*, through the rear part of the plate *f*, and remove a portion of the forward end of the latter, directly under the chimney.

The disconnected plate *f* measurably prevents the passage of heat to the cover *k*, and a shield, *m*, arranged beneath the handle, and covered on its top side with textile fabric, or some other suitable substance, *n*, not only shields the hand of the operator, but the woollen or other fabric, or other suitable covering, prevents burning the hand if brought into contact with the top of the shield.

A hole, *p*, through the rear end *G*, is convenient for lighting the gas, but no hole or opening is necessary in the end or sides of the flat-iron for any other purpose, since all the air required to support combustion passes through the burner-tubes, with the gas entering the hole *e*, which, in all cases, is wholly outside of the flat-iron.

It is evident that a hollow sad-iron could be heated with burners like these shown, if no posts or pillars were arranged within it, by applying such burners on a slight incline, that is, with their inner ends inclined or pointed slightly toward the bottom, as shown in fig. 4, and this would heat the bottom or face of the iron in a suitable manner.

In this invention, we do not claim a hollow sad-iron, nor do we claim a series of burners arranged beneath a disk; but

What we do claim, and desire to secure by Letters Patent, is—

The combination, with a hollow flat-iron, as described, of a series of gas-burners, constructed, arranged, and applied substantially in the manner and for the purpose specified.

ALBERT HALLOWELL.
ABEL T. ATHERTON.
